UNITED STATES PATENT OFFICE.

BERNARD NAGELVOORT, OF DETROIT, MICHIGAN, ASSIGNOR TO PACKARD MOTOR CAR COMPANY, OF DETROIT, MICHIGAN, A CORPORATION OF MICHIGAN.

ABRADING MACHINERY.

1,149,396.

Specification of Letters Patent. Patented Aug. 10, 1915.

Application filed February 10, 1913. Serial No. 747,483.

To all whom it may concern:

Be it known that I, BERNARD NAGELVOORT, a citizen of the United States, and resident of Detroit, Wayne county, State of Michigan, have invented certain new and useful Improvements in Abrading Machinery, of which the following is a specification.

This invention relates to cutting and abrading machinery, and the principal object of the invention is to provide an abrading device with means for collecting the dust produced by that device.

In the form of the invention shown and described herein, a rotary abrading disk is shown as entirely surrounded by a casing, which is arranged substantially in the plane of the disk, and the inner side of which is open to receive the cuttings or dust thrown from the periphery of the disk.

Another object of the invention is to so arrange the dust collecting casing about the abrading disk that it will not in any way interfere with the full working face of the disk.

Other objects of the invention will be apparent from the following description, taken in connection with the drawings which form a part of this specification, and in which,

Figure 1 is a perspective view of an abrading device embodying the invention; Fig. 2 is an elevation and part sectional view of the dust collecting casing; and Fig. 3 is partly a front elevation of the casing and disk, and partly a longitudinal section through the casing.

Referring to the drawings, 10 represents an abrading disk of any suitable construction, which is mounted in bearings 11 in a frame or support 12 and is driven through belt 13 and pulley 14 from any suitable source of power.

As is well known, in the use of abrading machines of the above described character, considerable dust is created, which is objectionable to the operator and is likely to get into the bearings of the machine if it is not properly gathered and disposed of. The present invention takes advantage of the centrifugal action of the grinding disk which tends to throw the dust directly away from the periphery of the face of the disk, and an annular casing 15 is provided to entirely surround the disk 10 and collect the

cuttings or dust thrown therefrom. The casing 15 is connected to an exhaust pipe 16 from which the air is exhausted by any suitable exhaust mechanism, not shown.

The inner side of the casing 15 is cut away, as shown particularly in Figs. 2 and 3, and a pair of annular deflector plates 17 are secured to the inner edges 18, as shown in said figures. These deflector plates are arranged to form a sort of trough, having their outer edges arranged adjacent each other and leaving a narrow opening or slit 19 between them, and having their inner edges separated or flared for the purpose of deflecting the cuttings or dust which are thrown from the periphery of the disk 10. The annular opening 19 is shown as being approximately in the plane of the face of the disk 10, which is probably its most advantageous position for gathering the cuttings and dust. The adjacent edges of the deflector plates 17 are tied together by suitable straps 20 secured thereto and arranged at intervals around the plates. This makes a more rigid construction and insures the opening or slit 19 being maintained at a given total area, which total area must be less than the cross sectional area of the interior of the casing 15 where it joins the exhaust pipe and of the exhaust pipe 16. It has been found by repeated experiments that it is of the utmost importance for the success of this machine that this opening 19 be maintained with a less area than the area of the exhaust pipe, as above set forth. It will be noted that the entire casing and deflector plates are entirely outside of the periphery of the disk 10, which permits of the use of the entire working face of the disk. A work table 21 is adjustably mounted upon a support 22 and arranged adjacent the working face of the disk and extends along one entire working radius thereof, as will be clearly seen in Fig. 1.

It is believed that the operation of the device will be clearly understood from the drawings and description, it being obvious that the dust created in the operation of the disk 10 against the work placed upon the table 21 will be thrown radially from the periphery of the disk 10 and deflected by the plates 17 toward the opening 19. Since air is being exhausted from the pipe 16, and hence from the interior of the casing 15,

there is a strong suction through the opening 19, which of course will carry with it all of the dust in the immediate vicinity. Thus practically all of the cuttings and dust created by the machine are carried away in the pipe 16 and the operator and the bearings of the machine are thereby protected.

A specific embodiment of the invention has been described in detail and will be 10 specifically claimed, but it is understood that the invention is not limited to the details shown, as it will be apparent that many changes may be made without departing from the spirit and scope of the invention.

Having thus described my invention, what I claim and desire to secure by Letters Patent is:

1. The combination with an abrading device, of a casing adjacent thereto having an opening to receive cuttings or dust therefrom, and an exhaust pipe connected to said casing, the cross-sectional area of said exhaust pipe being greater than the total area 25 of said opening.

2. The combination with a rotary abrading wheel, of a casing surrounding the periphery of said wheel and having an annular slit or opening partly in the plane of 30 said wheel, and an exhaust pipe connected to said casing.

3. The combination with a rotary abrading wheel, of a casing surrounding the periphery of said wheel and having an annular slit or opening partly in the plane of 35 said wheel, and an exhaust pipe connected to said casing, the cross-sectional area of said exhaust pipe being greater than the total area of said opening.

4. The combination with a rotary abrading wheel, of a casing surrounding the periphery of said wheel and having an annular slit or opening partly in the plane of 40 said wheel, deflecting means for directing

cuttings or dust from said wheel toward 45 said opening, and an exhaust pipe connected to said casing.

5. The combination with a rotary abrading disk, of an annular casing surrounding the periphery of said disk and having its 50 inner side open, annular deflector plates secured to said casing at its inner edges and providing a narrow opening between their adjacent edges, said opening being approximately in a plane with the face of said disk 55 and forming the inlet of said casing, and an exhaust pipe connected to said casing.

6. The combination with a rotary abrading disk, of an annular casing surrounding the periphery of said disk and having its 60 inner side open, annular trough-like deflector plates secured to said casing at its inner edges, and an exhaust pipe connected to said casing.

7. The combination with a rotary abrading disk, of an annular casing surrounding the periphery of said disk and having its 65 inner side open, annular trough-like deflector plates secured to said casing at its inner edges, said casing and plates being 70 entirely beyond the periphery of said disk, and an exhaust pipe connected to said casing.

8. The combination with a rotary abrading disk, of an annular casing surrounding 75 the periphery of said disk, annular deflector plates secured to said casing and forming between them an annular opening into the casing in a plane with the face of said disk, and an exhaust pipe connected 80 with said casing.

In testimony whereof I affix my signature in the presence of two witnesses.

BERNARD NAGELVOORT.
